UNITED STATES PATENT OFFICE.

FLORICEL A. ROJAS, OF NEW YORK, N. Y.

RHEOSTAT.

Application filed June 10, 1922. Serial No. 567,419.

To all whom it may concern:

Be it known that I, FLORICEL A. ROJAS, a citizen of the Republic of Santo Domingo, residing at New York, in the county of Bronx, State of New York, have invented certain new and useful Improvements in Rheostats; and I do hereby declare the following to be a full, clear, and exact description of the invention, such as will enable others skilled in the art to which it appertains to make and use the same.

This invention relates to compressible resistance rheostats of the types described in my U. S. Patents Nos. 1,315,579 and 1,366,945 and my copending application, Serial No. 546,149, and particularly to means for compressing and expanding the resistance material of such rheostats.

In rheostats of this type, the resistance material consists of a structureless mass of electrically non-conductive material, commonly asbestos wool, impregnated with conducting powders, such, for example, as conductive silicon and graphite. This material is confined between electrode plates, one of which is movable, and its resistance varied by varying the pressure exerted upon it by the plates. When the material is of relatively great lateral dimensions and slight thickness, variations in its resistance can be satisfactorily effected in this simple manner. When, however, it is necessary to design the resistor of less width, and greater thickness, either because of practical space considerations, or because the difference of potential between the electrode plates may be of such a magnitude that a thin layer of resistance material would not possess sufficient dielectric strength to prevent volt punctures and short circuiting of the instrument, it has been discovered that the material adjacent the movable plate is subjected to a much greater compression and expansion than that adjacent the stationary plate, due to the frictional resistance of the container walls, the internal frictional resistance of the material itself and sometimes to gravity. In other words, where the thickness of the resistance material is considerable, it does not act as a true homogenously elastic body, and most of the expansion and compression is effected in that part of the material adjacent the surface where the force is applied, that is, adjacent the moving electrode. This is, of course, objectionable. Where the resist-

ance material is secured to the movable plate so that positive expansion as well as compression is obtained, practically the entire potential drop takes place in the expanded zone, which means the development of a high temperature at this point with consequent danger of burning out. Even where the natural resistivity of the material is relied upon for expansion, the effective variable zone of the resistor is that immediately adjacent the movable plate, so that the range and efficiency of the instrument are greatly curtailed. Furthermore the resistance material when employed in substantial thicknesses is structurally weak and likely to separate during use with the formation of air gaps. It is an object of the present invention to provide means for overcoming these objections.

This object is attained by providing the resistance material at intervals along its thickness with a number of intermediate pressure distributing elements or plates which divide the resistance material into zones. They are designed to move in concert with the movable electrode but at progressively varying rates, the relative movement of all the plates being such that the zone of resistance material between any pair of them is compressed substantially the same amount as that between any other pair. The greater the number of these intermediate plates, the closer the compression of the material approaches that of a true elastic body and the stronger the material structurally, but by the use of four or five in an average instrument, practically satisfactory results can be had. In order to obtain this pantographic action a number of mechanical movements might conceivably be employed. In my copending application, Serial No. 546,149, the use of springs between the intermediate plates has been shown. I have secured the best results, however, by the use of a screw-threaded spindle, such as shown in the drawings forming a part of this application.

It is a further object of this invention to devise an improved thermostat for automatically compensating for variations in resistance due to the thermal expansion of the rheostat. The use of a metallic disc for this purpose was disclosed by me in my U. S. Patent No. 1,366,945, but there the heating of the thermostat was primarily by conduc-

tion from the resistor. In accordance with the present invention the thermostatic disc is made the stationary electrode and the current made to pass through a considerable 5 part of it so that it is heated not only by conduction and radiation but in accordance with Joule's law, because of its own electrical resistance.

Further objects of the present invention 10 are to devise more efficient means for cooling the interior of the resistor, and in general to improve rheostats of this type.

The invention will be more clearly understood after a study of the accompanying 15 drawings which disclose certain preferred embodiments of it. In these drawings Fig. 1 is a vertical section through a rheostat constructed in accordance with the present invention, and Fig. 2 is a similar view of a 20 very similar rheostat, but showing a certain modified form of construction.

The rheostat shown in these drawings comprises a metallic casing 1 closed at its upper end and opened at its lower. Within 25 this casing is mounted a cylindrical porcelain shell 2 which contains the resistor proper. This resistor is supported upon a metal plate 3 secured to the casing 1 by means of bolts or lag screws 4 and 5, which 30 pass through passageways in the porcelain shell 2 and therefore serve to hold the shell in position also. The upper ends of these bolts serve as the two binding posts 6 and 7 of the rheostat. They are insulated from 35 the casing 1, and bolt 5 is also insulated from the supporting plate 3. The inner face of this plate 3 is provided with an annular flange 8, upon which is mounted a metallic disc 9. This disc performs two 40 functions—it serves first as the stationary electrode of the rheostat and directly supports the resistance material, and it also serves as a thermostat, as will be described in greater detail later. Extending through 45 and journaled within the upper and closed end of the casing 1 is a spindle 11. That part of the spindle which lies within the casing is provided with a series of screw-threaded sections 12, 13, 14, 15 and 16. That 50 part which lies outside of the casing terminates in a hand wheel 17. The movable electrode 18 is mounted upon section 12 of the spindle and is electrically connected to the bolt 5 and the binding post 7 by means of lead 10. Mounted upon the other sections 55 13, 14, 15 and 16 are a series of intermediate pressure distributing plates 19, 20, 21 and 22 respectively. These plates and the movable electrode are secured to the resistance 60 material and divide it into a plurality of zones of equal thickness, the two outer zones contacting with the electrodes. The movable electrode and these intermediate plates are held against rotation by means of a fin or 65 key 23 projecting inwardly from the inner

face of the shell 2 and fitting within suitable notches 24 in the peripheral edges of the electrode and plates. It is therefore clear that upon rotation of the spindle the movable electrode and the pressure distributing 70 plates will be moved longitudinally thereof and hence exert a pressure against the resistance material at a plurality of points along its thickness. In the absence of the pressure distributing plates, movement of 75 the movable electrode would be effective only against what is shown as the upper zone of resistance material, and the lower zones would be neither compressed nor expanded an appreciable amount. In order, 80 however, to distribute the pressure throughout the thickness of the material so that it will act substantially as a true elastic body, it is necessary not only that the intermediate 85 plates exert a pressure upon the material but that the pressure exerted by any one of them must bear a predetermined relation to that exerted by the others. In other words, these plates and the movable electrode must be advanced and retracted as though they 90 themselves were elements in a true elastic body.

This effect is produced by suitably choosing the pitches of the threads on the various threaded sections so that when the spindle is 95 rotated the plates and electrodes approach each other at the same rate. For practical purposes I have chosen the following pitches. Section 12 contains five threads to the inch. section 13 six, section 14 eight, section 15 100 twelve and section 16 twenty-four. Thus upon one complete rotation of the spindle the movable electrode 18 will move one-fifth of an inch, plate 19 one-sixth of an inch, plate 20 one-eighth of an inch, plate 21 one-twelfth of an inch and plate 22 one-twenty-fourth of an inch. The difference between these movements is one-twenty-fourth of an inch, with the single exception of the difference between the movement of the movable electrode and plate 19. One-fifth of an inch is not exactly five-twenty-fourths, but it is close enough for practical purposes. By originally spacing the plates and the electrodes an equal distance from each other it 110 is clear that this distance will always be maintained, and the lowest zone, that adjacent the stationary electrode, will be subjected to substantially the same compression and expansion as that adjacent the movable 115 electrode.

Thus far the description is equally applicable to Figs. 1 or 2, as both forms of rheostat operate on exactly the same principle. The assembling of the parts of the resistor 125 proper presents some difficulties and the structures shown in the two figures illustrate two different ways in which this can be done. I shall first describe the assembling of the parts in connection with Fig. 1. It 130

is very important that a good electrical union be made between the resistance material and the various plate surfaces with which it comes in contact. It is also desirable that 5 a positive expansion as well as compression of the material be possible. For these two reasons the resistance material should be secured to the various plates and electrodes by means of a non-insulating adhesive. The 10 best adhesive of this nature which I know consists of a solution of metallic salts as described in my copending application, Serial No. 567,418. With a unitary spindle and one-piece plates it would be difficult to assemble 15 the parts and secure the zones of resistance material to the various contacting surfaces, as it would be necessary to rotate the plates when in contact with the material. For this reason I make the spindle shown 20 in Fig. 1 in a series of separable sections, each section carrying one of the sets of screw threads as shown, and each section being provided with a square head 25 at one end and a square socket 26 at the other 25 so that they can interfit as shown. As it is also necessary that the intermediate plates be insulated from the spindle as a whole, I have interposed a layer of insulation 27 between each of the interfitting sections. As shown, 30 the socket of each section, as well as the socket into which section 12 fits, is provided with a coating of vitreous enamel. In order that the assembled spindle should not come apart, a support is provided in the form 35 of a screw 28 provided with a conical tip and supported by the plate 3, passing upwardly through an opening 29 in the disc 9. The lowermost section 16 is provided with an insulating insert 31 with which the 40 screw 28 makes contact.

The resistor proper is assembled outside of the casing, the zones of the resistance material being secured by a suitable adhesive to their respective plates, mounted upon 45 their respective screw-threaded sections, and the parts put together without rotation of any of the plates. When assembly is complete the resistor proper is placed within the shell 2, the shell 2 placed within the casing 1, the screw 28 advanced to meet the end of the spindle, the proper connections made and the rheostat is in readiness for use.

In the form shown in Fig. 2, substantially the same result is obtained by providing 50 each intermediate plate with a separable hub 32 which is screwed upon the corresponding screw-threaded section of the spindle. These hubs are secured to the plates by means of screws 33 and are insulated from them. The spindle itself is also insulated from the casing. This structure also permits assembly of the plates without rotation. Here, as the spindle is in one piece, the supporting screw 28 shown in Fig. 1 is dispensed with.

In both figures the stationary electrode is in the form of a thin metallic disc 9. This disc, as stated above, also serves the function of a thermostat, expanding and bulging outwardly when hot and permitting a slight elongation of the resistance material which compensates for the increase in conductivity due to the internal expansion of the material. In order to regulate the bulging action of the thermostat a set screw 34 is provided. In Fig. 2 this set screw is located beneath the center of the disc. In the form shown in Fig. 1 this position is occupied by the supporting screw 28 so that two set screws 34 are employed, one on either side of the geometrical center.

I have discovered, however, in the form of rheostat shown in these figures, the current passing from the resistor through the annular flange 8 of the plate 3, that very little of the current actually passes through the disc 9, and therefore this disc is heated merely by radiation and conduction and not because of its resistance in accordance with Joule's law. This interferes with the sensitivity of the thermostat, and in order to force a substantial quantity of the current through the disc itself I have interposed an annular sheet of asbestos 35 between the resistance material and the peripheral surface of the disc. The greater the width of this annular sheet, the more the current passing through the disc itself.

In order to facilitate the cooling of the interior of the resistor I have drilled radial holes 36 in the intermediate plates, thus increasing their radiating surface and assisting in dissipation of the generated heat.

The operation of the rheostat, although probably clear from the foregoing, may be briefly reviewed as follows: Current enters at one of the binding posts, say at 7, passes through the lead 10 to the movable electrode 18, through the succeeding zones of resistance material and the intermediate plates, the stationary electrode and thermostat 9, plate 3, bolt 4 and binding post 6. The resistance of the rheostat varies with the pressure exerted upon the resistance material. This pressure, and consequently the resistance, is varied by turning the hand wheel 17 and causing the movable electrode and the intermediate plates to move toward and away from the stationary electrode. Movement of these parts is pantographic, and the instrument is designed so that the pressure exerted on each zone of resistance material is substantially the same as that exerted on any other, so that the resistance material as a whole acts under compression and expansion substantially like a true elastic body. By means of this instrument satisfactory use can be made of a compressible resistance rheostat in which the resistance material has a very substantial thickness,

and which if compressed or expanded as a whole would not only be inefficient electrically but weak structurally.

I claim:

5. 1. In a compressible resistance rheostat, the combination of a compressible resistance material, and means for applying force at a plurality of points along the thickness of the material to vary its resistance, 10 this force being distributed so that the material is compressed and expands as a substantially true elastic body.
15. 2. In a compressible resistance rheostat, the combination of a stationary electrode, a movable electrode, a compressible resistance material between these electrodes, a plurality of plates intermediate the electrodes dividing the resistance material into a plurality of zones, and means for moving 20 the movable electrode and the intermediate plates so that each zone is compressed and expanded substantially as every other zone.
25. 3. In a compressible resistance rheostat, the combination of a plurality of zones of compressible resistance material, and means for applying force to each zone so that each is compressed and expanded substantially the same as every other.
30. 4. In a compressible resistance rheostat, the combination of two relatively movable electrodes, a compressible resistance material held between them, a plurality of substantially equi-spaced plates intermediate the electrodes dividing the resistance material into equal zones, and means for effecting 35 a relative movement among the electrodes and the intermediate plates to vary the pressure upon and the resistance of the resistance material, the electrode and plates remaining substantially equi-spaced throughout.
45. 5. In a compressible resistance rheostat, the combination of two electrodes, one stationary and the other movable, a compressible resistance material situated between them, a plurality of plates intermediate the electrodes dividing the resistance material into zones, means for moving the movable electrode and the intermediate plates toward 50 and away from the stationary electrodes to vary the pressure upon and resistance of the resistance material, the movement of each being directly proportional to its distance from the stationary electrode.
55. 6. In a compressible resistance rheostat, the combination of two relatively movable electrodes, a resistance material confined between them, pressure distributing plates intermediate the electrodes dividing the resistance material into zones, a spindle having a number of threaded sections of different pitches on which are mounted one of the electrodes and the intermediate plates, 60 means preventing rotation of the electrodes and plates, and means for rotating the

spindle to move the electrodes and plates relative to one another and vary the pressure on the resistance material.

7. In a rheostat of the class described, a series of relatively movable pressure distributing plates dividing the resistance material into zones, a screw-threaded spindle having sections of different pitches on which the plates are mounted, means preventing rotation of the plates, and means for rotating the spindle to cause movement of the plates longitudinally thereof, the relation of the different pitches being such that the plates approach each other at the same rate. 75

8. In a rheostat of the class described, the combination of relatively movable electrodes, resistance material held between them, pressure distributing means intermediate the electrodes, and pantographic means acting upon one of the electrodes and the pressure 85 distributing means to move them in such a way that the resistance material is compressed and expanded as a whole in substantial conformity with elastic laws.

9. In a rheostat of the class described, a series of relatively movable pressure distributing plates secured to the resistance material and dividing it into zones, a screw-threaded spindle having sections of different pitches on which the parts are mounted, means preventing rotation of the plates, means permitting assembly of the plates on the spindle without rotation, and means for rotating the spindle to cause movement 95 of the plates longitudinally thereof. 100

10. In a rheostat of the class described, a series of relatively movable pressure distributing plates, dividing the resistance material into zones, a screw-threaded spindle having separable threaded sections of different pitches on which the plates are mounted; means preventing rotation of the plates, and means for rotating the spindle to cause movement of the plates longitudinally thereof, the relation of the different pitches being such that the plates approach each other at the same rate. 105

11. In a compressible resistance rheostat, the combination of a movable electrode, a stationary electrode, resistance material confined between them, pressure distributing plates intermediate the electrodes, a composite screw-threaded spindle having separable threaded sections, the movable electrode and the intermediate plates being mounted one on each of the separable threaded sections, and a support for the spindle extending upwardly from the stationary electrode. 115

12. In a compressible resistance rheostat, the combination of a movable electrode, a stationary electrode, resistance material confined between the pressure distributing plates intermediate the electrode, a composite screw-threaded spindle having separable threaded sections insulated from each 125 130

other, the movable electrode and the intermediate plates being mounted, one on each of the separable threaded sections, and a support for the spindle insulated from it 5 extending upwardly from the stationary electrode.

13. In a compressible resistance rheostat, the combination of a movable electrode, a metallic thermostatic disc serving as a stationary electrode, resistance material between the two, and means causing the current passing through the resistance material to pass through a substantial part of the thermostatic disc and heat it in accordance 10 with Joule's law.

14. In a compressible resistance rheostat, the combination of a movable electrode, a metallic thermostatic disc serving as a stationary electrode, resistance material between the two, means causing the current passing through the resistance material to pass through a substantial part of the thermostatic disc and heat it in accordance with 20 Joule's law, and means for regulating the 25 expansion of the thermostatic disc.

15. In a compressible resistance rheostat, the combination of a movable electrode, a metallic thermostatic disc serving as a stationary electrode, resistance material between the two, means making electrical contact with the thermostatic disc at its periphery, an annular sheet of insulating material interposed between the resistance material and the peripheral surface of the 30 thermostatic disc to cause the current to pass through a substantial part of the thermostatic disc and heat it in accordance with Joule's law.

16. In a compressible resistance rheostat, 40 the combination of two relatively movable electrodes, resistance material confined be-

tween them, pressure distributing plates intermediate the electrodes and having openings within them facilitating the cooling of the resistor.

45

17. A rheostat comprising the combination of a casing closed at one end and open at the other, a shell of insulating material within the casing, a stationary electrode closing the shell at the open end of the casing, a movable electrode within the shell at the closed end of the casing, resistance material held between the electrodes, and means extending through the closed end of the casing for moving the movable electrode. 50 55

18. In a compressible resistance rheostat, the combination of two relatively movable electrodes, a compressible resistance material, held between them, a plurality of substantially equi-spaced plates intermediate the electrodes dividing the resistance material into two equal zones, the resistance material adhering to the electrodes and plates so that it can be positively expanded as well as compressed, and means for effecting a relative 60 65 movement among the electrodes and the intermediate plates to vary the pressure upon and the resistance of the resistance material, the electrode and plates remaining substantially equi-spaced throughout. 70

19. In a compressible resistance rheostat, the combination of two relatively movable electrodes, a metallic thermostatic disc serving as one of the electrodes, resistance material between the two, and means causing 75 the current passing through the resistance material to pass through a substantial part of the thermostatic disc and heat it in accordance with Joule's law.

In testimony whereof I affix my signature.

FLORICEL A. ROJAS.
